ELECTROLYTIC CELL

Adriaan Hendrik Willem Aten, Hilversum, Netherlands, assignor to American Enka Corporation, Enka, N. C., a corporation of Delaware

Application March 9, 1938, Serial No. 194,966

2 Claims. (Cl. 204—219)

This invention relates to an electrolytic cell that is particularly useful in recovering metals and acids from aqueous solutions of their salts. In particular, this invention is directed to an electrolytic cell for electrolyzing aqueous solutions of alkali metal salts to recover the alkali metal hydroxide and acid therefrom.

Prior to this invention, many types of mercury cathode cells have been proposed for the purpose of decomposing alkali metal salts and recovering the alkali metals therefrom, but the lack of sufficiently large cathode surfaces, the failure of the mercury in these surfaces to be agitated so as to present continuously fresh surfaces to the solution in the cell, gas formation at the cathode, collecting of the gas below the diaphragm, the necessity of a large volume of mercury, excessive current drop in the cell due to excessive distance between the anode and the cathode, and numerous other difficulties which the present device also eliminates have prevented these cells from being entirely satisfactory.

The present device is similar in some respects to prior devices, for example, a mercury cathode cell and a diaphragm to separate the anode and cathode solutions are utilized. The arrangement of the present cell is such, however, that the cathode constantly presents large areas of fresh mercury to the solution and the anode is quite close to the cathode and parallel to a plane through the centers of the troughs holding the mercury. Substantially even spacing of the anode and cathode is made possible by providing narrow troughs and by using an anode of suitable shape. Furthermore, the diaphragm is so arranged that it aids in the elimination of the gas formed on the cathode instead of collecting the gas. Numerous other structural details of the present device which contribute to make it more satisfactory and which are a part of this invention will be apparent from the following detailed description of the preferred form of this device as shown in the appended drawing.

Figure 1 is a side sectional view of the device and

Figure 2 is a fragmentary sectional view of this device taken along the line 2—2 of Figure 1.

As illustrated, the cell consists of a body member 11, which may be cast or stamped or otherwise fabricated from iron or other metal or from glass, hard rubber, wood, or any other desired non-metallic material. When this body member is made of a material that conducts electricity, such as a metal, it has been found nec-

essary to line it with a non-conductive material, such as ebonite, Celluloid, glass, or a synthetic resin. Such a lining is shown in the drawing and indicated by the reference numeral 12.

The configuration of the body member 11 is such as to provide a tank or cell in which the electrolysis may be accomplished and to provide at the bottom of this tank or cell a series of weirs 13 which divide the bottom of the tank into a plurality of flat pans or troughs 14. These troughs 14 are arranged so as to be progressively lower from one side of the bottom of the vessel toward the other side so that mercury placed in the highest trough and caused to overflow, will overflow into the next lower trough and this action will be continuous until the mercury has passed through each of the pans and reached the lowest. Appropriate means are provided to insure continuous passage of the mercury from one trough to the next so that the cathode surface is always spread over the area defined by all of the troughs. For example, a small slot may be present alternately near the far and the near end of each subsequent trough in the direction of flow of the mercury. An inlet 15 is provided for the mercury, which inlet opens into the highest pan and an outlet 16 is also provided for removing the mercury amalgam from the lowest pan.

Above the mercury cathode arrangement, the body member 11 is formed so as to receive and support a diaphragm 17, which diaphragm extends completely across the cell and separates the portion of the cell adjacent the cathode from the rest of the cell. An anode 18 is placed above the diaphragm so as to be separated from the cathode by the diaphragm.

The diaphragm 17 is held by the body member 11 in a position which is inclined to the horizontal so that the hydrogen given off at the cathode passes upward along the under surface of the diaphragm and out of the cell. The incoming salt solution enters through an opening 19 in the wall of the body member 11, this opening is made sufficiently large to allow the hydrogen, coming off from the mercury, to escape, and is situated just below the diaphragm. The diaphragm is preferably of porous ebonite, but might be of acid-resistant asbestos fiber, a mat of glass fiber held together by an acid-resistant binder, 50 or a ceramic material such as corundum or porous tile.

In addition to being supported by the body member 11 at the side walls, the diaphragm is preferably also supported by the top edges of the

- weirs 13 by resting thereon. In order to prevent the mercury in the cathode from coming in contact with the diaphragm, the weirs are constructed as shown in Figure 2 with raised portions 20 5 which support the diaphragm and lower portion 21 over which the mercury passes into the next lower pan. These raised portions are shaped so as to collect as little hydrogen as possible and thereby assist in the elimination of the hydrogen.
- 10 In the form of the device shown in the drawing, the anode 18 which is preferably made of perforated sheet lead or alloy thereof is situated above the diaphragm. The current of liquid which flows from the cathode to the anode shows 15 a tendency to carry the diaphragm in upward direction. In order to keep a space between the diaphragm and the anode the latter is provided with protruding ridges which prevent the diaphragm from coming into contact with the whole 20 surface of the anode.

25 The top of the cell is open to the air so that any oxygen formed at the anode may pass through the perforations thereof, bubble to the top of the liquid in the cell, and escape or, if desired, be collected. An outlet 22 is provided in the wall of the cell above the anode through which the acidic anode liquid may be discharged.

30 In operation, a solution of sodium sulphate or similar salt of a reactive metal enters the cell 30 through the opening 19, passes downward along the diaphragm, and runs through the diaphragm into the upper portion of the cell where it reaches the anode. As it does so, it is electrolyzed and reduced at the mercury cathode to form an amalgam; at the anode sulphuric acid is formed with 35 evolution of oxygen. The acid liquid is discharged through the opening 22 and the amalgam drawn off through the outlet 16. The metal so recovered may then be removed from the amalgam 40 in any of the usual ways. The mercury thus recovered after removal of said metal is recirculated through the system. Current may be supplied to the anode and the mercury cathode in the usual way, as by the connections 23 and 45 24, respectively.

The conditions under which the present invention is practiced may be varied; but by way of example, it has been determined that a neutral solution of sodium sulphate at a tempera-

ture of 5° to 10° C. above its saturation point will give an anode liquor of 10% to 15% sulphuric acid containing approximately 13% of sodium sulphate. Hence, the device allows a current-output of 90-97%, depending on the 5 10 acidity required in the anode-liquor and a bath tension of 5.5-7 volts depending on the current-density. Under the aforementioned conditions the electrodes are separated an average distance of less than two inches, for example 0.7 of one 10 inch. The most effective current density is from 100 to 250 amperes per square foot.

15 The amalgam passes off at outlet 16 to be converted into an alkali metal hydroxide.

What I claim is:

1. In an electrolytic cell for recovering sodium and sulphuric acid from sodium sulphate, the combination of a series of troughs containing mercury arranged to provide a cascade type of mercury cathode, a diaphragm positioned above 20 the cathode and supported on the edges of the troughs of the cathode in a position generally parallel to the cathode in the direction of its inclination, an anode positioned above the diaphragm and supported thereon and also generally parallel to the cathode in the direction of its inclination, an inlet to the cathode compartment to supply sodium sulphate solution exclusively to that compartment, and an outlet from the anode compartment to remove sul- 30 phuric acid from that compartment.

2. In an electrolytic cell for recovering sodium and sulphuric acid from sodium sulphate, the combination of a series of troughs containing mercury arranged to provide a cascade type of 35 mercury cathode, a diaphragm positioned above the cathode and supported on the edges of the troughs of the cathode in a position generally parallel to the cathode in the direction of its inclination, a foraminous anode positioned above 40 the diaphragm and also generally parallel to the cathode in the direction of its inclination, an inlet to the cathode compartment to supply sodium sulphate solution exclusively to that compartment, and an outlet from the anode com- 45 partment to remove sulphuric acid from that compartment.

ADRIAAN H. W. ATEN.
